UNITED STATES PATENT OFFICE.

CLARENCE BERNARD CALLOMON, OF SOUTH ORANGE, NEW JERSEY, ASSIGNOR TO
DRIVER-HARRIS COMPANY, OF HARRISON, NEW JERSEY, A CORPORATION OF
NEW JERSEY.

BOX FOR HEAT-TREATING METALLIC ARTICLES.

1,387,236.

Specification of Letters Patent.

Patented Aug. 9, 1921.

Application filed October 28, 1920. Serial No. 420,185.

To all whom it may concern:

Be it known that I, CLARENCE B. CALLOMON, a citizen of the United States, residing at South Orange, county of Essex, State of New Jersey, have invented a certain new and useful Improvement in Boxes for Heat-Treating Metallic Articles, of which the following is a full, clear, and exact description.

10 My invention relates to boxes for use in the heat treatment of metallic articles, such boxes, for instance, as carburizing boxes, annealing boxes and the like, and has for its object to produce a box in which the danger 15 of warping due to internal and external heating are practically eliminated. It further has for its object to produce a box such that a plurality of such boxes can be packed close together in the furnace and still permit 20 free circulation of heated air and gases around them. It further has for its object to produce a box in which the weight of material forming the box will be less than in a rectangular box of the same capacity. It 25 further has for its object to produce a box which will require less carburizing compound when used as a carburizing box than a rectangular box for a given number of articles to be treated. It further has for its 30 object to produce a box in which the time for producing a given result by heat treatment is reduced. It further has for its object to produce a self-sealing box and one of less height for a given capacity.

35 The following is a description of a box embodying my invention, in which—

Figure 1 represents, partly in end view and partly in transverse section, a box embodying my invention piled upon others of 40 the same sort;

Fig. 2 is a side elevation of one box and a portion of another similar box on which the first box rests;

Fig. 3 is a plan view of one box body; 45 and,

Fig. 4 is a reverse plan view of the cover.

Referring more particularly to the drawings, 1 is a box body having a wall 2 formed so as to have substantially true inner and outer cylindrical surfaces starting 50 near the mouth on one side and extending to a similar point on the other side. The axes of these surfaces coincide in the center of the box. The hollow cylindrical body thus

formed is closed at its ends by end portions 3 formed integral therewith. The lower portions of the two ends are provided with extensions 4 having straight lower surfaces substantially in line with the plane tangent to the bottom of the box body. 4' is a similar extension at the center of the box body. The upper portions of the sides are provided with vertical flanges 5, which connect with internally projecting flanges 6 on the ends so as to surround the opening constituting the mouth of the box. This opening is a lateral opening extending approximately from end portion to end portion, being an elongated opening nearly corresponding in length with the internal longitudinal dimension of the box.

7 is a cover of flat metal provided with a downwardly projecting flange 8 extending around the same at a slight distance from its edge so as to fit snugly within the opening at the top of the box, the cover resting on the tops of the extensions 5 and 6.

In making such a box I use any metal heretofore used for heat treatment boxes according to the temperature used in the heat treating process. Thus they may be made of cast iron for comparatively low temperatures. For high temperatures, I prefer to use the nickel, chromium, iron alloys, such as specified in Patent No. 1,270,519, granted 85 to J. C. Henderson on June 25, 1918.

A suitable box is about 47 inches long and 13 $\frac{1}{2}$ inches in internal diameter, the walls and ends being about $\frac{5}{16}$ of an inch in thickness. The extensions forming the legs 4 and 4' are only of such width as will maintain the box in upright position, their width being less than that of the cover.

The box may be made by casting, or the cylindrical part may be made of rolled sheet 95 metal, the ends being cast thereon.

Boxes of the shape described, on account of their cylindrical walls, practically eliminate the danger of warping when they are subjected to the necessary temperatures employed in the heat treatment. The stresses due to external heating conditions are equal in all directions about the circumference of the box and there is no straight surface upon their sides to get the full effect of an impinging flame which would set up bending stresses. A flame impinging on the side of a box such as described would tend to cir-

culate at a tangent thereto and there could therefore be no direct flame action thereon.

Moreover, warping which might be caused by stresses set up inside a box, due to the generation of heat by the packing compound is also prevented, the circumferential stresses on the inside due from such causes being also equal at all points on the inside of the cylinder.

10 Furthermore, the boxes can be packed closer together in a furnace, as shown in Figs. 1 and 2, and still allow free circulation of heat around them on account of the spaces 9 which are necessarily present. Except for the small contact of the extensions 4 and 4' with the covers and the theoretical line of contact between a cover and the box body of a superimposed box, all portions of the box and cover are exposed to the hot air 15 or gases of the furnace.

Furthermore, with a box of this tubular shape, the amount of metal necessary for producing a box of a given productive capacity is very much smaller than the amount 20 necessary for boxes of shapes heretofore used. Furthermore, the tubular shape results in a very considerable saving of the carbonizing compound which it is necessary to use over what is necessary for a rectangular box, since there are no corners at the 25 sides of the box which it is necessary to fill.

The elimination of these corners, together with the resulting reduction in the carbonizing material also results in enabling the 30 metallic parts to be heat treated to be closer to the internal surface of the box, with the result that they are heated more quickly and in this way the length of the heating period for a given hardening operation is reduced.

40 The height of the box is also reduced for a box of a given length and width, since it

requires no legs or runners to permit the circulation of heat beneath the box.

The cover is so shaped that it is self-sealing, making it unnecessary to use any luting 45 compound.

The invention therefore attains the objects above stated.

As will be evident to those skilled in the art, my invention permits of various modifications without departing from the spirit thereof or the scope of the appended claims. 50

What I claim is:

1. A box for heat treating metallic articles, comprising a hollow cylindrical body portion having an opening on one side constituting the mouth of the box, said opening extending approximately the full length of said body portion, vertical end closing portions for said box body, and a cover for said 60 box.

2. A box for heat treating metallic articles, comprising a hollow cylindrical body portion having an opening on one side constituting the mouth of the box, said opening 65 extending approximately the full length of said body portion, vertical end closing portions for said box, and a cover for said box, said box having on its bottom leg portions terminating substantially in a plane tangent 70 to the bottom of said box.

3. A box for heat treating metallic articles, comprising a hollow cylindrical body portion having an opening on one side constituting the mouth of the box, said opening 75 extending approximately the full length of said body portion, vertical end closing portions for said box body, and a cover for said box, said cover extending over said flanges and having a downward projection fitting 80 said mouth.

CLARENCE BERNARD CALLOMON.
